UNITED STATES PATENT OFFICE.

TURE ROBERT HAGLUND, OF STOCKHOLM, SWEDEN, ASSIGNOR TO INTERNATIONAL PATENT CORPORATION, A CORPORATION OF MARYLAND.

PROCESS OF TREATING ORES CONTAINING A REFRACTORY OXIDE.

No Drawing. Original No. 1,569,483, dated January 12, 1926, Serial No. 579,964, filed August 5, 1922.
Application for reissue filed October 29, 1927. Serial No. 229,786.

The object of the present invention is: out of oxidic raw materials containing several oxides to separate one or more oxides, for example SiO_2 , Fe_2O_3 , CaO etc. This 5 separation or purification is according to the present invention effected by a process wherein the oxide or oxides from which the raw material is to be purified, are separated by reduction or by conversion into non- 10 oxidic compounds by the smelting of the raw material containing the oxides in question, for example in an electric furnace, together with sulphurous materials and the necessary reducing agents, the process being 15 carried out in such a way as to result in the formation of a melt containing both sulphide and oxide, but entirely or essentially free from the oxides to be separated, i. e. in such a way that the melted mass is substantially 20 free from such oxides from which the raw material is to be purified. The melt containing sulphide and oxide thus obtained can be used for various purposes: thus, for example, if its oxide content consists entirely, 25 or in essentials, of aluminum oxide, it may be used as raw material for the manufacture of alloys. As in the cooling of the sulphide-oxide melt, its content of oxide substantially 30 crystallizes, the melt is moreover very well adapted for the production, of pure or purified oxides, or of oxide compounds or mixtures of oxides purified from injurious oxides, which is effected by the separation 35 of the sulphide content, for example by treatment of the crystallized melt with acids, alkalies, water or steam.

Should the sulphide-oxide melt not be sufficiently pure, it may be subjected to remelting, for example together with reducing agents and, if necessary, additional admixtures of sulphurous materials.

The process is particularly well adapted for the production of aluminium oxide, especially of the kind which is sufficiently 45 pure to be used for the manufacture of pure aluminium metal by melt-electrolysis. As in the process the aluminium oxide is obtained in a crystallized form, it can also be used

for grinding purposes, for example for the manufacture of grinding discs, or the like. 50 Moreover, aluminium oxide, produced in accordance with the present process is a very suitable material for the manufacture of refractory bricks. If, for example, in order to attain a certain grinding action, it is desired that the aluminium oxide should contain other oxides, this may be effected by regulating the reduction in suitable way during the smelting and, if necessary, by the addition during the smelting of any special 55 admixtures that may be required. The process is also suitable for the manufacture of other oxides. Thus, it is possible in accordance with the process to manufacture crystallized magnesium oxide, either pure or 60 with a certain desired content of other oxides.

As crystallized magnesium oxide manufactured in accordance with the process does not, like amorphous oxide, show a great tendency to shrink at high temperatures, it is particularly well adapted for the manufacture of refractory bricks. Amongst other oxides which can be manufactured in a crystallized form in accordance with the process 75 may, as example, be mentioned, alkaline earth oxides, zirconia (zirconium-oxide), and others.

As the process is of great importance for the manufacture of aluminium oxide, such 80 manufacture is by way of example described in greater detail here below:

I first produce a melt containing as its principal component a mixture of Al_2O_3 and one or more sulphides, for example Al_2S_3 , 85 which have the capacity of dissolving aluminium oxide in a molten state, but out of which melt aluminium oxide crystallizes on cooling, is first of all made. This melt containing oxide and sulphide may be produced 90 for example by smelting in an electric arc furnace the raw material in the presence of reducing agents, such as coke, small coal, charcoal, calcium carbide, etc. in order entirely or essentially to reduce certain oxides, 95 such as SiO_2 , Fe_2O_3 , FeO , TiO_2 , etc, which

together with Al_2O_3 are contained in the raw materials. By treating this melt so that the sulphide is decomposed and separated off, or dissolved out, a crystal mass consisting of practically pure aluminium oxide is obtained.

The most suitable raw material containing Al_2O_3 for the manufacture of aluminium oxide in this manner is bauxite, but it is also possible to employ other minerals, or the like containing Al_2O_3 , such as chamotte, feldspar, alum schists, leptite, clays, for example those containing carbon, coal waste containing Al_2O_3 and others, as well as products containing Al_2O_3 manufactured in accordance with some method, such as, for example, alundum contaminated by SiO_2 or FeO . Several different kinds of raw materials containing aluminium may, of course, be used simultaneously or together.

The following may serve as examples of the process for the manufacture of a sulphide-alumina melt of the kind above referred to:—

25 *Example 1.*—Bauxite—if desired after previous drying and heating to incandescence—is melted in an electric furnace together with ferrous sulphide and coal. The coal is added in a quantity sufficient to reduce ferro-, silico-, and titanic oxygen compounds in the bauxite, and, for example, 25% of the Al_2O_3 in the bauxite. The reduced iron, silicon and titanium alloy themselves in the main with one another, and 30 the alloy sinks to the bottom in the furnace. The reduced aluminium is converted with FeS into iron, which enters as an ingredient into the alloy, and Al_2S_3 , which absorbs by dissolving the remaining Al_2O_3 in the bauxite, if desired, the quantity of FeS can be so chosen that part of the reduced aluminium metal is obtained in the alloy, with a view to diminish the risk of too high a content of sulphur in the said alloy. The 35 smelting should preferably be carried on continuously. In this way there will be obtained on tapping the furnace partly ferro-silicon or the like and partly a sulphide-alumina melt in which latter, on cooling, 40 Al_2O_3 crystallizes out.

45 *Example 2.*—Bauxite, which may be calcined, is melted, preferably in an electric furnace, together with reducing agents in a quantity sufficient to reduce in the main 50 oxides such as FeO , SiO_2 , TiO_2 , etc., which in addition to Al_2O_3 are present in the bauxite and a sulphide, for example CaS or Al_2S_3 . The Al_2O_3 in the bauxite is thereby 55 dissolved by the sulphide, and then crystallizes on cooling. Ferro-silicon is moreover obtained. In order to be assured of obtaining reduced silicon bound in the alloy, it is also suitable to charge iron in some form, for example iron filings, or else a ferro-com- 60 pound together with reducing agents.

As is evident from the above examples, the sulphide in the sulphide-alumina melt can be obtained in the processes by the addition of sulphides with a lower heat of formation than Al_2S_3 , which sulphides are 70 converted with aluminium, or, in the presence of reducing agents, with Al_2O_3 , into aluminium sulphide. If it desired to obtain a sulphide other than Al_2S_3 in the sulphide-alumina melt, one may add substances 75 which in the presence of the sulphide admixtures above referred to give rise to sulphide with a higher heat of formation than Al_2S_3 . Such admixtures may, for example, consist of CaO , MgO , BaO , or others, 80 or else compounds or raw materials containing such substances, or again alloys or metals containing substances which give rise to sulphides with a higher equivalent generating heat than Al_2S_3 , as, for example, ferro-manganese. Sulphides of the kind above indicated suitable for the process, i. e. such 85 which have a lower heat of formation than Al_2S_3 , are sulphides of heavy metal such as FeS , Cu_2S , etc. It is also possible to use minerals, or other products containing such sulphides, for instance magnetic iron pyrites (Fe_3S_4), for example a nickeliferous kind of such pyrites, ordinary pyrites, copper pyrites, copper glance, galena, crude copper (copper matte) ore etc. Obviously also other sulphur compounds of these metals, such as sulphates, may be employed, which however require a special reducing agent to convert them into sulphides. It is also possible to employ simultaneously several of the above mentioned sulphur compounds.

In lieu of, or simultaneously with, the above sulphur compounds, it is also possible to employ one or more sulphides which have an equal or higher equivalent generating heat than Al_2S_3 , which sulphides in the main do not undergo chemical transformation in the process, but enter into the sulphide-alumina melt as the sulphide or sulphides which in a molten state constitute the solvent for Al_2O_3 . Sulphides suitable for this purpose are, for example, Al_2S_3 , sulphides of alkali and alkaline earth metals, such as K_2S , Na_2S , BaS , CaS , MgS , etc. These sulphides may be exchanged wholly or partially for the corresponding sulphates or sulphites, for example, CaSO_4 , BaSO_4 , etc., together with reducing agents required for their reduction. In certain cases sulphur also may be used as an admixture for the formation of the required sulphide, for instance if any carbide, for example calcium carbide, is employed as a reducing agent in the process.

In the procedure according to Example 2 it was stated that a separate addition of iron could be made in order to ensure that silicon should be bound in the alloy. The iron, both in this and in other forms of the process

may obviously be replaced entirely or partially by some other metal, e. g. copper, moreover in order to obtain such metal, the admixtures may obviously consist of metal oxides, e. g. Fe_2O_3 , FeO , Fe_3O_4 , etc., together with reducing agents.

The quantity of sulphide in the sulphide alumina melt may obviously be varied within wide limits. It is suitable to work with 10 a sulphide content of 20-40%, but in certain cases a considerably lower content may suffice, for example down to 10% or lower. In case of a higher content of sulphide the crystals will be larger, whence, if large crystals 15 are desired, one should work with a high percentage of sulphide, e. g. up to 75% or more. The size of the crystals may also be regulated by changes in the rate of cooling of the sulphide-alumina melt.

20 The sulphide-alumina melt is far more fusible than Al_2O_3 , and in determining the percentage of sulphide, the obtaining of a low melting-point may also be taken into consideration.

25 The sulphide-alumina melt separates itself easily from the alloy simultaneously obtained, and is treated after the cooling for the production of Al_2O_3 . This procedure may, for example, be carried out by treating the 30 melt, preferably after crushing, with some acid, e. g. H_2SO_4 , HCl , HNO_3 , acetic acid, etc. or a mixture of two or more such acids. By this means the sulphide is decomposed and dissolved. The melt is as a rule contaminated with heavy metal sulphide, e. g. 35 FeS . On the melt being dissolved with acid in excess, this impurity enters into solution. As an undissolved remainder is obtained a 40 crystal mass of Al_2O_3 , which, if necessary, can be freed by washing or decanting from minor impurities insoluble in the acid, e. g. SiO_2 , and, if desired, it may be treated for the same purpose with alkaline lye, e. g. 45 $NaOH$. The crystal mass of Al_2O_3 is then dried.

50 If the sulphide-alumina melt contains Al_2S_3 it is possible out of the solution obtained in the treatment of the melt if necessary after purifying from impurities such as salts of iron to produce aluminium hydrate and to produce out of the latter pure Al_2O_3 , or else the solution may be used for the production of aluminium salts, e. g. aluminium sulphate.

55 The dissolution of the sulphide in the sulphide-alumina melt may also be carried out in two or more stages. This is especially advisable if the sulphide consists of aluminium sulphide. If a deficit of acid is used the first time, there will be obtained a solution practically free from iron, as the iron sulphide is not dissolved until practically all the 60 Al_2S_3 is dissolved. In the treatment of the remainder with new acid in excess, the remainder of the Al_2S_3 and any FeS that occurs will be dissolved. On the dissolving of the

melt in acid H_2S is developed which may be collected or utilized separately.

Instead of dissolving with acid, it is possible, if the sulphide consists of a sulphide easily decomposed or dissolved by water, 70 such as Al_2S_3 , Na_2S , etc., first to treat the sulphide-alumina melt with water or steam. "Water" as used in the accompanying claims includes steam. If the sulphide consists, for example, of Na_2S , K_2S , or BaS , it enters 75 into solution on being treated with water. If the sulphide consists of Al_2S_3 , it is decomposed under the development of H_2S and the formation of aluminium hydrate. The aluminium hydrate can then be dissolved 80 with acids or alkalies and be treated for the production of pure Al_2O_3 , or for aluminium salts, or else the aluminium hydrate can be separated by washing or stirring and decanting from the crystal of Al_2O_3 . The 85 latter should then be treated with acid for the dissolving of any impurities, such as FeS . The washed or decanted aluminium hydrate can, after drying and eventually heating to redness, be used as raw material 90 for renewed production of a sulphide-alumina melt, or else be used as raw material for the manufacture of pure Al_2O_3 , or aluminium salts, for example in accordance with methods which in themselves are known. 95

Any metal, magnetic sulphide or the like which may occur in the alumina crystal mass or in the decanted aluminium hydrate may eventually be separated by methods commonly employed in the separation of ore, 100 such as by magnetic or electrostatic separation, etc.

The manufacture of other oxides in accordance with the process is carried out in a manner analogous to the procedure for the 105 manufacture of Al_2O_3 . In the manufacture of crystallized MgO burned magnesite may, for example, be used as raw material. The chief impurities in the latter are CaO , SiO_2 , and Fe_2O_3 . The separation of these 110 oxidic impurities may for example be carried out by smelting the magnesite together with such a quantity of a reducing agent that SiO_2 and Fe_2O_3 are reduced and that CaO and possibly some MgO react with a sulphurous 115 admixture made for the purpose, for example magnetic iron pyrites or FeS , and form CaS and MgS . The remaining MgO will then be dissolved in a molten condition into the calcium and magnesium sulphides and will crystallize on cooling. CaS and MgS are separated off afterwards, e. g. by soaking with water or diluted acids. 120

Having thus described my invention I declare that what I claim is:

1. The process of treating ores containing iron, silicon or titanium and a refractory metal oxide which does not fuse below $1940^{\circ}C$. comprising reducing oxides of iron, silicon or titanium and dissolving the refrac- 130

tory oxide in a sulfide containing slag by fusing the ore with a sulfide yielding material and a reducing agent, the proportion of sulfide containing material being such that 5 a part of the refractory metal oxide remains unconverted in the slag and separating the reduced iron, silicon or titanium from the sulfide-refractory-oxide slag.

2. The process of treating ores containing 10 iron, silicon or titanium and a refractory metal oxide which does not fuse below 1940° C. comprising reducing oxides of iron, silicon or titanium and dissolving the refractory metal oxide in a sulfide containing slag 15 by fusing the ore with a sulfide yielding material and a reducing agent, the proportion of sulfide-containing material being such that the slag contains not to exceed 75% of sulfide, the balance of the slag being formed 20 by the dissolved refractory oxide and separating the reduced iron, silicon or titanium from the sulfide-refractory-oxide slag.

3. The process of treating ores containing 25 iron, silicon or titanium and a refractory metal oxide which does not fuse below 1940° C. comprising reducing oxides of iron, silicon or titanium and dissolving the refractory oxide in a sulfide containing slag by fusing the ore with metallic sulfides and a 30 reducing agent, the proportion of the metallic sulfides being such that a part of the refractory metal oxide remains unconverted in the slag and separating the reduced iron, silicon or titanium from the sulfide-refrac- 35 tory-oxide slag.

4. The process of removing oxides of iron, silicon or titanium from ores containing a difficultly reducible metal oxide which does not fuse below 1940° C., which comprises 40 heating the ore with a metallic sulfide and a reducing agent, the proportion of metallic sulfide being such that a part of the difficultly reducible metal oxide remains unconverted in the slag and tapping and separating 45 the reduced iron, silicon or titanium and the sulfide-refractory-oxide slag.

5. The process of removing oxides of iron, silicon or titanium from ores containing refractory metal oxides which do not fuse below 1940° C., which comprises heating the ore with metallic sulfides and a reducing agent, the proportion of metallic sulphides being such that a part of the refractory metal oxides remains unconverted in the 50 slag, separating the reduced iron, silicon or titanium from the sulfide-refractory-oxide slag and separating the refractory oxides from the slag.

6. The process of removing oxides of iron, 60 silicon or titanium from ores containing refractory metal oxides which do not fuse below 1940° C., which comprises heating the ore with metallic sulfides and a reducing agent, the proportion of metallic sulfides being such that a part of the refractory

metal oxides remains unconverted in the slag, separating the reduced iron, silicon or titanium from the sulfide-refractory-oxide slag, and separating the refractory oxides from the slag.

7. The process of removing oxides of iron, silicon or titanium from ores containing metal oxides which do not fuse below 1940° C., which comprises heating the ore with metallic sulfides having a heat of formation 70 not higher than aluminum sulfide and a reducing agent, the proportion of metallic sulfides being such that a part of the metal oxides remains unconverted in the slag and tapping and separating the reduced iron, silicon or titanium and the sulfide-refractory-oxide slag.

8. The process of removing oxides of iron, silicon or titanium from ores containing difficultly reducible metal oxides which do not 85 fuse below 1940° C., which comprises heating the ore with metallic sulfides having a heat of formation not higher than aluminum sulfide and a reducing agent, the proportion of the metallic sulfides being such that the slag 90 contains not to exceed 75% of sulfide, the balance of the slag being formed by the dissolved metal oxides and tapping and separating the reduced iron, silicon or titanium and the sulfide-refractory-oxide slag.

9. The process of removing oxides of iron, silicon or titanium from ores containing refractory metal oxides which do not fuse below 1940° C., which comprises heating the ore with metallic sulfides having a heat of 100 formation not higher than aluminum sulfide and a reducing agent, the proportion of metallic sulphides being such that a part of the refractory metal oxides remains unconverted in the slag, separating the reduced iron, silicon or titanium from the sulfide-refractory-oxide slag and separating the refractory oxides from the slag.

10. The process of removing oxides of iron, silicon or titanium from ores containing refractory metal oxides which do not fuse below 1940° C., which comprises heating the ore with metallic sulfides having a heat of formation not higher than aluminum sulfide and a reducing agent, the proportion of metallic sulphides being such that a part of the refractory metal oxides remains unconverted in the slag, separating the reduced iron, silicon or titanium from the sulfide-refractory-oxide slag and separating the refractory oxides from the slag.

11. The process of treating ores containing iron, silicon or titanium and aluminum oxide comprising reducing oxides of iron, silicon or titanium and dissolving the aluminum oxide in a sulfide containing slag by fusing the ore with a sulfide yielding material and a reducing agent, the proportion of sulfide-yielding material being such that a part of the aluminum oxide remains un- 120 125 130

converted in the slag; and separating the sulfide-aluminum-oxide slag from the reduced iron, silicon or titanium.

12. The process of treating ores containing iron, silicon or titanium and aluminum oxide comprising reducing oxides of iron, silicon or titanium and dissolving the aluminum oxide in a sulfide containing slag by fusing the ore with a sulfide yielding material and a reducing agent, the proportion of sulphide being such that a part of the aluminum oxide remains unconverted in the slag, separating the sulfide-aluminum-oxide slag from the reduced iron, silicon or titanium and separating the aluminum oxide from the slag.

13. The process of treating bauxite comprising reducing oxides of iron, silicon and titanium and dissolving aluminum oxide in a sulfide containing slag by fusing the bauxite with a sulfide yielding material and a reducing agent, the proportion of sulfide-yielding material being such that the slag contains not to exceed 75% of sulfide, the balance of the slag being formed by the dissolved aluminum oxide and separating the sulfide-aluminum-oxide slag from the reduced alloy.

14. The process of treating bauxite comprising reducing oxides of iron, silicon and titanium and dissolving aluminum-oxide in a sulfide containing slag by fusing the bauxite with a sulfide yielding material and a reducing agent, the proportion of sulphide being such that a part of the aluminum oxide remains unconverted in the slag, separating the sulfide-aluminum-oxide slag from the reduced alloy and separating the aluminum oxide from the slag.

15. The process of treating ores containing aluminum oxide comprising reducing oxides of iron, silicon or titanium and dissolving aluminum-oxide in a sulfide containing slag by fusing the ore with a sulfide and a reducing agent, the proportion of sulfide being such that a part of the aluminum oxide remains unconverted in the slag, and separating the sulfide-aluminum-oxide slag from the reduced iron, silicon or titanium.

16. The process of treating ores containing aluminum-oxide comprising reducing oxides of iron, silicon or titanium and dissolving aluminum-oxide in a sulfide containing slag by fusing the ore with a sulfide and a reducing agent, the proportion of sulphide being such that a part of the aluminum oxide remains unconverted in the slag, separating the sulfide-aluminum-oxide slag from the reduced iron, silicon or titanium and separating the aluminum-oxide from the slag.

17. The process of treating bauxite comprising reducing oxides of iron, silicon and titanium and dissolving aluminum oxide in a sulfide containing slag by fusing the bauxite with a sulfide and a reducing agent,

the proportion of sulfide being such that a part of the aluminum oxide remains unconverted in the slag and separating the sulfide-aluminum-oxide slag from the reduced alloy.

18. The process of treating bauxite comprising reducing oxides of iron, silicon and titanium and dissolving aluminum-oxide in a sulfide containing slag by fusing the bauxite with a sulfide and a reducing agent, the proportion of sulphide being such that a part of the aluminum oxide remains unconverted in the slag, separating the sulfide-aluminum-oxide slag from the reduced alloy and separating the aluminum oxide from the slag.

19. The process of treating ores containing iron, silicon or titanium and aluminum-oxide comprising reducing oxides of iron, silicon or titanium and dissolving the aluminum-oxide in a sulfide containing slag by fusing the ore with a sulfide having a heat of formation not higher than that of aluminum sulfide and a reducing agent, the proportion of sulfide being such that the slag contains not to exceed 75% of sulfide, the balance of the slag being formed by the dissolved aluminum oxide and separating the sulfide-aluminum-oxide slag from the reduced iron, silicon or titanium.

20. The process of treating ores containing iron, silicon or titanium and aluminum oxide comprising reducing oxides of iron, silicon or titanium and dissolving aluminum-oxide in a sulfide containing slag by fusing the ore with a sulfide having a heat of formation not higher than that of aluminum sulfide and a reducing agent and separating the sulfide-aluminum-oxide slag from the reduced iron, silicon or titanium and separating out the pure aluminum-oxide from the slag.

21. The process of treating bauxite comprising reducing oxides of iron, silicon and titanium and dissolving aluminum-oxide in a sulfide containing slag by fusing the bauxite with a sulfide having a heat of formation not higher than that of aluminum sulfide and a reducing agent, the proportion of sulfide being such that a part of the aluminum oxide remains unconverted in the slag and separating the sulfide-aluminum-oxide slag from the reduced alloy.

22. The process of treating bauxite comprising reducing oxides of iron, silicon and titanium and dissolving aluminum-oxide in a sulfide containing slag by fusing the bauxite with a sulfide having a heat of formation not higher than that of aluminum sulfide and a reducing agent and separating the sulfide-aluminum-oxide slag from the reduced alloy, and separating out the pure aluminum-oxide from the slag.

23. The process of removing oxides of iron, silicon or titanium from ores contain-

ing aluminum oxide which comprises fusing the ore with an iron sulfide and a reducing agent and tapping and separating the sulfide-aluminum-oxide slag and the reduced iron, silicon or titanium and cooling the slag for crystallizing the aluminum oxide.

24. The process of removing oxides of iron, silicon or titanium from ores containing aluminum oxide, which comprises fusing

10 the ore with an iron sulfide and a reducing agent and separating the sulfide-aluminum-oxide slag from the reduced iron, silicon or titanium and separating out the pure aluminum oxide from the slag.

15 25. The process of removing the oxides of iron, silicon and titanium from bauxite, which comprises fusing it with an iron sulfide and a reducing agent and tapping and separating the sulfide-aluminum-oxide slag 75 and the reduced iron-silicon-titanium alloy and cooling the slag for crystallizing the aluminum oxide and regulating the size of the crystals by the rate of cooling.

20 26. The process of removing the oxides 25 of iron, silicon and titanium from bauxite, which comprises fusing it with an iron sulfide and a reducing agent and separating the sulfide-aluminum-oxide slag from the reduced iron-silicon-titanium alloy and separating out the pure aluminum oxide from the slag.

25 27. The process of removing oxides of iron, silicon or titanium from ores containing aluminum oxide, which comprises fusing 100 the ore with an iron sulfide and carbon and tapping and separating the sulfide-aluminum-oxide slag and the reduced iron, silicon or titanium and cooling the slag for crystallizing the aluminum oxide.

30 28. The process of removing oxides of iron, silicon or titanium from ores containing aluminum oxide, which comprises fusing the ore with an iron sulfide and carbon and separating the sulfide-aluminum-oxide slag from the reduced iron, silicon or titanium, and separating out the pure aluminum oxide from the slag.

35 29. The process of removing the oxides of iron, silicon and titanium from bauxite, which comprises fusing it with an iron sulfide and carbon and tapping and separating the sulfide-aluminum-oxide slag and the reduced iron-silicon-titanium alloy and cooling the slag for crystallizing the aluminum oxide and regulating the rate of cooling for forming comparatively small crystals.

40 30. The process of removing the oxides of iron, silicon and titanium from bauxite, which comprises fusing it with an iron sulfide and carbon and separating the sulfide-aluminum-oxide slag from the reduced iron-silicon-titanium alloy and separating out the pure aluminum oxide from the slag.

45 31. The process of removing oxides of iron, silicon or titanium from ores contain-

ing aluminum oxide, which comprises fusing the ore with iron pyrites and carbon, and tapping and separating the sulfide-aluminum-oxide slag and the reduced iron, silicon or titanium and cooling the slag for 79 crystallizing the aluminum oxide.

32. The process of removing oxides of iron, silicon or titanium from the ores containing aluminum oxide, which comprises fusing the ore with iron pyrites and carbon 75 and separating the sulfide-aluminum-oxide slag from the reduced iron, silicon or titanium and separating out the pure aluminum oxide from the slag.

33. The process of removing the oxides of iron, silicon and titanium from bauxite, which comprises fusing it with magnetic iron pyrites and carbon and tapping and separating the sulfide-aluminum-oxide slag and the reduced iron-silicon-titanium alloy 85 and cooling the slag for crystallizing the aluminum oxide and regulating the rate of cooling for forming comparatively small crystals.

34. The process of removing the oxides of iron, silicon and titanium from bauxite, which comprises fusing it with magnetic iron pyrites and carbon and separating the sulfide-aluminum-oxide slag from the reduced iron-silicon-titanium alloy and separating out the pure aluminum oxide from the slag.

35. The process of removing oxides of iron, silicon or titanium from ores containing aluminum oxide, which comprises forming 100 a sulfide-aluminum-oxide slag containing up to about 75 per cent of sulfide by fusing the ore with a metallic sulfide and carbon, the proportion of sulphide being such that a part of the aluminum oxide remains unconverted in the slag, and separating the sulfide-aluminum-oxide slag from the reduced iron, silicon or titanium.

36. The process of removing oxides of iron, silicon or titanium from ores containing aluminum oxide, which comprises forming a sulfide-aluminum-oxide slag containing up to about 75 per cent of sulfide by fusing the ore with a metallic sulfide and carbon, the proportion of sulphide being such that a part of the aluminum oxide remains unconverted in the slag, separating the sulfide-aluminum-oxide slag from the reduced iron, silicon or titanium and separating the aluminum oxide from the slag.

37. The process of removing iron, silicon and titanium from bauxite, which comprises forming a sulfide-aluminum-oxide slag containing up to about 75 per cent of sulfide by fusing bauxite with iron sulfide and carbon, the proportion of sulphide being such that a part of the aluminum oxide remains unconverted in the slag and separating the sulfide-aluminum-oxide slag from the reduced iron-silicon-titanium alloy.

38. The process of removing iron, silicon and titanium from bauxite, which comprises forming a sulfide-aluminum-oxide slag containing up to about 75 per cent of sulfide by 5 fusing bauxite with iron sulfide and carbon, the proportion of sulphide being such that a part of the aluminum oxide remains unconverted in the slag, separating the sulfide-aluminum-oxide slag from the reduced 10 iron-silicon-titanium alloy and separating the aluminum oxide from the slag.

39. The process of removing oxides of iron, silicon or titanium from ores containing aluminum oxide, which comprises forming 15 a sulfide-aluminum-oxide slag containing from about 10 up to about 40 per cent of aluminum sulfide by fusing the ore with a metallic sulfide and carbon and separating the aluminum-sulfide-aluminum-oxide slag 20 from the reduced iron, silicon or titanium.

40. The process of removing oxides of iron, silicon or titanium from ores containing aluminum oxide, which comprises forming a sulfide-aluminum-oxide slag containing 25 from about 10 up to about 40 per cent of aluminum sulfide by fusing the ore with metallic sulfide and carbon and separating the aluminum-sulfide-aluminum-oxide slag from the reduced iron, silicon or titanium 30 and decomposing the aluminum sulfide and separating out the pure aluminum oxide.

41. The process of removing oxides of iron, silicon and titanium from bauxite, which comprises forming a sulfide-aluminum-oxide slag containing from about 10 up to about 40 per cent of aluminum sulfide by 35 fusing bauxite with iron sulfide and carbon and separating the aluminum-sulfide-aluminum-oxide slag from the reduced iron-silicon-titanium alloy.

42. The process of removing oxides of iron, silicon and titanium from bauxite, which comprises forming a sulfide-aluminum-oxide slag containing from about 10 up to about 40 per cent of aluminum sulfide by 45 fusing bauxite with iron sulfide and carbon and separating the aluminum-sulfide-aluminum-oxide slag from the reduced iron-silicon-titanium alloy and decomposing the 50 aluminum sulfide and separating out the pure aluminum oxide.

43. The process of removing oxides of iron, silicon or titanium from ores containing a difficultly reducible metal oxide 55 which does not fuse below 1940° C., which comprises dissolving the difficultly reducible metal oxide in a sulfide-containing slag by fusing the ore with a reducing agent and materials yielding a sulfide separable 60 through water, and treating the sulfide-refractory-oxide slag with water to separate the refractory oxide.

44. The process of treating ores containing a difficultly reducible refractory oxide 65 comprising removing oxides of iron, silicon

or titanium by heating the ore with reducing agents and dissolving the refractory oxide in a sulfide decomposable through water, and treating the sulfide-refractory-oxide-slag with water for decomposing sulfide and separating the refractory oxide from the decomposed slag. 70

45. The process of treating ores containing aluminum oxide comprising removing oxides of iron, silicon or titanium and dissolving aluminum oxide in a sulfide-containing slag by fusing the ore with a reducing agent and materials yielding a sulfide separable through water, cooling the sulfide-aluminum-oxide slag for crystallizing the 80 aluminum oxide and treating the slag with water to separate the aluminum oxide.

46. The process of treating ores containing aluminum oxide comprising removing oxides of iron, silicon or titanium through 85 reduction and dissolving aluminum oxide in a slag containing a sulfide decomposable by water and treating the slag with water to decompose sulfide.

47. The process of treating ores containing aluminum oxide comprising removing oxides of iron, silicon or titanium through reduction and dissolving aluminum oxide in a slag containing a sulfide decomposable by 90 water, cooling the sulfide-aluminum-oxide slag to crystallize the aluminum oxide and thereupon decomposing the sulfide by treating the slag with water and separating the aluminum oxide from the decomposed slag. 95

48. The process of removing oxides of iron, silicon and titanium from bauxite, which comprises forming a sulfide-aluminum-oxide slag containing aluminum sulfide by fusing bauxite with a sulfide having a 100 heat of formation less than that of aluminum sulfide and a reducing agent, crystallizing the aluminum oxide by cooling the slag and decomposing aluminum sulfide by treating the slag with water. 105

49. The process of removing oxides of iron, silicon and titanium from bauxite, which comprises forming a sulfide-aluminum-oxide slag containing aluminum sulfide by fusing bauxite with an iron sulfide and carbon, cooling the slag to crystallize the 110 aluminum oxide, decomposing the aluminum sulfide by treating the slag with water and thereupon separating formed aluminum hydrate from the crystallized aluminum oxide. 115

50. The process of removing iron, silicon or titanium oxides from ores containing aluminum oxide, which comprises fusing the ore with a sulfide having a heat of formation not higher than that of aluminum sulfide and carbon in such amounts that a sulfide-aluminum-oxide slag containing aluminum sulfide in a quantity less than 40 per cent is formed, and decomposing aluminum sulfide by treating the slag with water. 120 125

51. The process of treating bauxite, which comprises removing oxides of iron, silicon and titanium and forming a sulfide-aluminum-oxide slag containing from about 10 up to about 40 per cent of aluminum sulfide by fusing bauxite with an iron sulfide and carbon, crystallizing aluminum oxide by

cooling the slag, thereupon decomposing aluminum sulfide in the slag with water and separating formed aluminum hydrate from ¹⁰ crystallized aluminum oxide.

In testimony whereof I have hereunto affixed my signature.

TURE ROBERT HAGLUND.
